UNITED STATES PATENT OFFICE.

ELEAZER KEMPSHALL, OF NEWTON, MASSACHUSETTS, ASSIGNOR TO
THEOPHILUS KING, TRUSTEE, OF BOSTON, MASSACHUSETTS.

DESIGN FOR AN EYELET.

SPECIFICATION forming part of Design No. 25,862, dated August 4, 1896.

Application filed November 13, 1895. Serial No. 568,864. Term of patent 14 years.

To all whom it may concern:

Be it known that I, ELEAZER KEMPSHALL, of Newton, in the county of Middlesex and State of Massachusetts, have invented and 5 produced a new and original Design in Eyelets, of which the following is a specification.

This invention relates to a new and original design for eyelets; and it consists in the novel shape and configuration hereinafter 10 fully described and particularly claimed, and clearly illustrated in the drawings.

Reference is to be had to the accompanying sheet of drawings, forming a part of this application, in which like characters are used to indicate like parts wherever they occur.

Figure 1 represents a perspective view showing my design. Fig. 2 represents a longitudinal section thereof.

The essential feature of my design consists in a tubular-shaped body provided near one 20 end with a plurality of apertures.

a represents a tubular-shaped body; *a'*, the apertures formed in one end thereof.

I claim—

The design for an eyelet, substantially as 25 shown and described.

In testimony whereof I have signed my name to this specification, in the presence of two subscribing witnesses, this 11th day of November, A. D. 1895.

ELEAZER KEMPSHALL.

Witnesses:

C. F. BROWN,
E. BATCHELDER.
